(Cl. D48—20)

To all whom it may concern:

Be it known that we, Edward J. Ries and Clarence G. Maxson, citizens of the United States of America, residing respectively at Brighton and Rochester, in the county of Monroe and State of New York, have invented a new, original, and ornamental Design for a Dental Lighting Unit, of which the following is a specification, reference being had to the accompanying drawings, forming part thereof.

In the drawings:

Fig. 1 is a front elevational view of a dental lighting unit, embodying our new design;

Fig. 2 is a side elevation looking from the right of Fig. 1;

Fig. 3 is a rear elevation;

Fig. 4 is a side elevation looking from the right of Fig. 3; and

Fig. 5 is a top plan view of the dental lighting unit.

We claim:

The ornamental design for a dental lighting unit, substantially as shown.

EDWARD J. RIES.

CLARENCE G. MAXSON.
